UNITED STATES PATENT OFFICE.

FREDERICK A. HART, OF HARTFORD, CONNECTICUT, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,213,100.

Specification of Letters Patent. Patented Jan. 16, 1917.

Application filed July 3, 1911. Serial No. 636,593.

To all whom it may concern:

Be it known that I, FREDERICK A. HART, a citizen of the United States, residing in Hartford, in the county of Hartford and 5 State of Connecticut, have invented certain new and useful Improvements in Combined Type-Writing and Computing Machines, of which the following is a specification.

This invention relates to computing machines, particularly those of the Underwood-Hanson type illustrated in my pending application No. 466,836, filed December 10, 1908, in which the keys of the typewriter control the setting of certain pins, and the 15 pins afterward coöperate with the general operator to turn the adding wheels.

One of the principal objects of my invention is to provide simplified and improved means readily applicable to existing machines, for guarding against errors which 20 arise from the liability of the operative to forget to attend to the operation of the general operator after said pins have been set for a number.

According to the present improvements, a locking bar is provided which is normally out of use, but which is automatically thrown into use at the operation of the key which sets the unit pin for any number, thus 25 locking the numeral keys and preferably all of the keys of the typewriter, so that new pins cannot be set up before the computing wheels have been operated to register the number previously set up on said pins. Said 30 locking bar is connected to said general operator to be released thereby, so that when the machine is properly operated, the lock moves automatically into and out of effective position, without interfering at all with 35 the operation of the keys; but at any time when the operative forgets to attend to the general operator, after depressing the numeral keys, he will be reminded of the omission by finding that the keys of the typewriter will not operate.

I preferably employ the same bar that is used in the line-locking mechanism of the Underwood typewriting machine for locking the keys at the completion of a line of 40 writing; and I so construct the machine that the usual function of said bar can be performed; while it is also thrown into effective position at the operation of any numeral key to write a digit in the units place in a

column of writing. I provide means normally under tension for moving said bar from normal idle position to effective position; but said means are normally restrained by a latch; and I provide means controlled by the carriage of the typewriter for releasing said latch when the carriage is in a position just succeeding the writing of the units digit of a number. Upon operating the general operator, the parts are restored to normal positions. 55

In the accompanying drawings, Figure 1 is a sectional side elevation of an Underwood-Hanson combined typewriting and adding machine, showing the present improvements applied thereto; the parts being 60 in normal positions, and the keys free to operate. Fig. 2 is a diagram of the key locking parts in effective positions at the writing of the digit in the units place in a column. Fig. 3 is a perspective rear view 70 of the present improvements. Fig. 4 shows a shiftable fulcrum for a special jack. Fig. 5 is a plan of the jacks. Fig. 6 is a front elevation of the jacks, showing a special jack as having returned to normal position during the movement of the paper carriage immediately following the impress of a digit type in the units place. Fig. 7 shows the special jack as being operated, during a movement of the carriage to the Fig. 6 po- 75 sition. 80

Numerical keys 1 and letter keys 2 depress levers 3 to operate through bell cranks 4, to throw type bars 5 upwardly and rearwardly to strike upon the front side of a platen 6, 90 which is mounted to travel upon a letter-feeding carriage 7, which is driven in the usual manner by a spring 8, and is controlled by letter-feeding devices connecting a universal bar 9 actuated by heels 10 on the 95 type-bars, and forming part of a frame 11 which has vibrating supports 12 and actuates the usual letter-feeding dogs 12^a, to control escapement wheel 12^b. Upon said carriage is a tappet 13, which is usually ad- 100 justable along the rack bar 14, and has a cam edge to lift in succession jacks 15 arranged in a row mounted upon a fulcrum 16. The denomination selector or tappet 13 may be made ineffective by swinging it on its 105 mounting around the bar 13^a as described in my co-pending application No. 466,836, cited above. The rear ends 17 of the jacks press

down links 18 to vibrate levers 19, which are connected to linkages 20 to lift the rear ends of a series of denominational or order bars 21, whose forward ends carry racks 22 to mesh with pinions 23 provided upon dial wheels 24, whereby the latter may be rotated. The numeral keys 1 have stems 25 to operate arms 26 upon linkages 27 to depress any of a set of pins 28 upon the elevated rack bar. As the carriage 7 feeds step-by-step, the rack bars 21 are elevated in succession, and downwardly from each one is projected a pin 28. The rack bars fall to normal positions, thus bringing the depressed pins into the path of a cross bar 29 forming part of a general operator. The general operator, which also comprises a pair of arms 30 and a pair of racks 31 on opposite sides of the machine, is connected by pinions 32 and segments 33 to a shaft 34 which carries the operating handle 35. After the pins are set up by the numeral keys 1 to register a number temporarily, the operative grasps the handle 35 and the general operator is slid forwardly, the bar 29 engaging all of the depressed pins and driving forward the racks 22 corresponding distances, to turn the dial wheels 24 accordingly.

Upon striking a key 1 to print a digit in the units place in the column, and then releasing said key, the carriage 7 advances one step, and the tappet 13 engages a special jack 36 placed at the end of the row of jacks 35 and having a link 37 to engage arm 38 upon a rock shaft 39 to rock the latter; said shaft carrying an upstanding arm 40 to which is pivoted the rear end of a latch 41, whereby said latch is withdrawn rearwardly from a tooth or shoulder 42 formed on an upstanding rod 43, which is then driven up by a spring 44, the latter connected to one arm 45 of a bell crank, and the other arm 46 of said bell crank carrying said rod 43. In this upward movement, the rod 43 strikes an arm 47 projecting rearwardly from a rock shaft 48, which, in the Underwood typewriting machine, has arms 49, 50 to carry a bar 51, swinging the same forward under hooks 52 formed on all the key-levers 53. Hence when the paper carriage moves one step after the writing of a digit in the units place, the keys 1, 2 are locked, Fig. 2. The operator now grasps the handle 35 to move forward the general operator, and a cam or shoulder 54 on the bar or slide 31 engages the lower end of an arm 55 of a bell crank, comprising another arm 56 and mounted upon a rock shaft 57, and by means of a link 58 restores the bell crank 45, 46 to normal position, together with the lock-setting rod 43, permitting the usual spring 59 to restore said locking bar 51 to normal idle position. At the same time, a spring 60 connected to an arm 61 on rock shaft 39 restores the latter to nor-

mal position, together with the rod 37 and jack 36.

As will be seen at Fig. 7, the nose 62 of the jack 36 is made very thin, and the tappet 13 is of such form that the jack 36 will be operated (Fig. 7) and released (Fig. 6) by the time the paper carriage 7 completes its first letter-feeding movement after the writing of a digit in the units place; and hence the latch 42, after releasing the lock-operating bar 43, is caused by the spring 60 to tend to re-latch said rod, so that when the latter is pulled down by the arm 56 and link 58, the latch 42 snaps into place to hold the rod 43 down in normal position. The link 58 is formed with a slot 63 to engage a pin 64 in said arm 56 to permit reciprocation of the general operator at any time, without obstruction from said link 58. The rock shafts 39 and 57, and the bell crank 55, 56 may also be used for other purposes, as set forth in said application. After reciprocating the handle 35, and thereby throwing the locking bar 51 back to idle position, the operative may manipulate the keys 1 to set up pins for the next number, and upon the writing of a digit in the next units place the latch 42 will be again withdrawn, and the cycle of operations repeated. Thus, by simple means readily applied to the machine, errors arising from failure to manipulate the handle 35 are avoided.

By turning a button 63, the special jack 36 can be moved to a position to silence or disable the key-locking mechanism. This button is mounted upon the outer end of a stub shaft which is eccentric to the shaft 16 that carries the jacks 35; and on the inner portion of said shaft 64 is a stud 65 which normally is concentric with the shaft 16, and which, by rotation of the button 63 through a half revolution, is lifted above the shaft 16, so that the nose 62 of the special jack 36 is raised too high to be engaged by the tappet 13. It will be seen at Fig. 5, that stud 65 abuts against the end of the shaft 16, which is suitably supported in a bracket or casing 66 independently of said stud 65. To hold the stub shaft 64 where adjusted, a spring 67 presses a ball 68 into a seat 69, Fig. 4, formed in the stub shaft, said spring being held down by a screw 70, Fig. 1. The stub shaft may have depressions on its opposite sides, and these depressions may be connected by a shallow peripheral groove 71.

Variations may be resorted to within the scope of the invention, and portions of the improvements may be used without others.

Having thus described my invention, I claim:

1. In a combined typewriting and computing machine having a typewriter carriage, numeral keys and computing mechanism; an obstructing means for the keys comprising a device normally tending to

obstruct said keys, a latch restraining said obstructing device, and means dependent on the movement of the carriage for releasing the latch.

5 2. In a combined typewriting and computing machine having a typewriter carriage, numeral keys, computing mechanism and a manually controlled general operator for running numbers into the computing mechanism; and comprising in combination, a device normally tending to obstruct said keys, a latch restraining said obstructing device, means dependent upon the movement of said carriage for releasing said latch to permit said device to obstruct the keys to warn the operative to operate the general operator, and means controlled by said general operator for releasing said keys from said obstructing device.

20 3. In a combined typewriting and computing machine having a typewriter carriage, numeral keys, computing mechanism and a manually controlled general operator for running numbers into the computing mechanism; and comprising in combination, a device normally tending to obstruct said keys to warn the operative to operate said general operator, a latch restraining said obstructing device, means dependent upon the movement of said carriage for releasing said latch, means controlled by said general operator for releasing said keys from said obstructing device, and a spring for returning said latch to the position where it is effective to restrain the obstructing device.

4. In a combined typewriting and computing machine having a typewriter carriage, numeral keys, computing mechanism and a manually controlled general operator for running numbers into the computing mechanism; and comprising in combination, a bar for locking said keys at the end of a line of writing, an independent device normally tending to set said line-locking bar to operative position, said bar being movable to operative position independently of said bar-setting device, a latch restraining said bar-setting device, and means dependent upon the writing of a digit in the units place in a column for releasing said latch to permit said locking device to become effective to warn the operative to operate said general operator.

5. In a combined typewriting and computing machine having a typewriter carriage, numeral keys, computing mechanism and a manually controlled general operator for running numbers into the computing mechanism; and comprising in combination, a bar for locking said keys at the end of a line of writing, an independent device normally tending to set said line-locking bar to operative position, said bar being movable to operative position independently of said bar-setting device, a latch restrain-

ing said bar-setting device, means dependent upon the writing of a digit in the units place in a column for releasing said latch to lock the keys to warn the operative to operate the operator, and means dependent upon the movement of said general operator for replacing said bar-setting device under the control of said latch.

6. In a combined typewriting and computing machine having a typewriter carriage, numeral keys, computing mechanism including computing wheels and a general operator for running into the computing mechanism numbers set by said keys; and comprising in combination, a row of jacks, one for each wheel, connections whereby the general operator operates the wheels selected by said jacks to an extent determined by said keys, a jack-setting device dependent upon the movement of the carriage, a special jack following the units jack in said row, means normally tending to lock said keys, a latch normally restraining said locking means, and means connected to said special jack for releasing said latch to lock said keys and thereby notify the operative to operate the general operator.

7. In a combined typewriting and computing machine having a typewriter carriage, numeral keys, computing mechanism including computing wheels and a general operator for running into the computing mechanism numbers set by said keys; and comprising in combination a row of jacks, one for each wheel, connections whereby the general operator operates the wheels selected by the jacks to an extent determined by said keys, a jack-setting device dependent upon the movement of the carriage, a special jack following the units jack in said row, means normally tending to lock said keys, a latch normally restraining said locking means, means connected to said special jack for releasing said latch to lock the keys to warn the operative to operate the operator, and means controlled by said general operator for restoring the key-locking devices to normal positions to reset the parts for a new computation.

8. A combined typewriting and computing machine having a typewriter carriage, numeral keys, computing mechanism and a manually controlled general operator for running numbers into the computing mechanism; and comprising in combination a device normally tending to lock said keys against action, a latch restraining said locking device, means dependent upon the movement of said carriage for releasing said latch to lock said keys thereby notifying the operative to operate the general operator, and means controlled by said general operator for releasing said keys from said locking device to reset the parts for a new computation; said general operator being oper-

able independently of said key-locking and releasing means when the latter are in normal positions.

9. In a combined typewriting and computing machine, the combination with a carriage and numeral keys controlling said carriage, of computing mechanism including a general operator and also including a denominational row of members, a jack following the last of said denominational row of members, a line locking bar for said keys, a spring for normally holding said bar in ineffective position, a device to set said bar to effective position, a spring tending to operate said bar-setting device, a latch normally restraining said bar-setting device and a connection from said latch to said jack to operate the latch for the purpose of making said locking bar effective to warn the operative to operate the general operator.

10. In a combined typewriting and computing machine, the combination with a carriage, numeral keys, and means to control said carriage by said numeral keys, of a computing mechanism including a general operator and also including computing wheels, a denominational row of members, one for each of said wheels, a jack following the last of said denominational row of members, a line lock bar for said keys, said bar normally held in an ineffective position, means to set said bar to an ineffective position, a spring tending to operate said bar-setting means, a latch normally restraining said spring and said bar-setting means, a bell crank connected to said latch, and a link connecting said bell crank to said jack, whereby said jack may release said latch to permit the movement of said bar to a position in locking engagement with said keys.

11. In a combined typewriting and computing machine including a letter-feeding carriage and type-operating keys, the combination with computing devices including denominational members controlled by said carriage, of means dependent upon the movement of the carriage to lock said keys, said locking means including a part shiftable at will to a position to disable said locking means while the denominational members still remain active.

12. In a combined typewriting and computing machine, the combination with a carriage and numeral keys having means to control the same, of computing mechanism including temporarily registering devices and a manually controlled general operator and also including computing wheels or devices turned by said operator to an extent determined by said registering devices, and a row of denominational members, one for each wheel, a jack following the last of said denominational row of members, means normally tending to lock said keys, a latch normally restraining said locking means, means

connected to said jack for releasing said latch to warn the operative to operate said operator, and means to set said jack to ineffective position and hold it there.

13. The combination with means for temporarily setting up a number, computation accumulating means, means for transferring the numbers set up to said accumulating means, obstructing means for preventing further setting up of a number when the last digit of the number has been set up, means normally tending to shift said obstructing means to obstructing position, a latch for restraining said shifting means and means brought into action by the temporary setting up means for releasing said latch.

14. In a combined typewriting and computing machine, the combination with a carriage and numeral keys having means to control said carriage; of computing mechanism including computing wheels and a row of jacks one jack for each wheel, a special jack following the units jack in said row, a jack setting device dependent upon the movement of the carriage for operating all of said jacks, a device for obstructing said keys, and means controlled from said jack setting device and acting through the medium of said special jack for controlling the effectiveness of said obstructing means.

15. In a combined typewriting and computing machine, the combination with a carriage and numeral keys controlling the same, of computing mechanism including a general operator and also including computing wheels and a row of jacks, one jack for each wheel, a special jack following the units jack in said row, a jack setting device dependent upon the movement of the carriage for operating all of said jacks, a device for obstructing said keys, means controlled by said jack setting device and acting through the medium of said special jack for rendering said obstructing means effective, and means controlled by said general operator for rendering said obstructing device ineffective.

16. The combination with means for temporarily setting up a number, computation accumulating means, means for transferring the numbers set up to said accumulating means, obstructing means for preventing further setting up of a number when the last digit of the number has been set up, means normally tending to shift said obstructing means to obstructing position, a latch for restraining said shifting means, means brought into action by the temporary setting up means for releasing said latch and means for restoring said latch to operative position brought into action by transferring the number set up to the accumulating means.

17. In a combined typewriting and com-

- puting machine, the combination with a carriage and numeral keys controlling the same, of computing mechanism including computing wheels and a row of denominational selecting jacks one jack for each wheel, a special jack following the units jack in said row, a jack setting device dependent upon the movement of the carriage to operate all of said jacks, a key obstructing device controlled by said special jack, and means to set and hold said special jack in ineffective position in respect to said jack setting device while said device is still effective on said denominational jacks.
18. The combination with a computation-accumulating means, of computation-registering means, a general operator for transferring an accumulated computation from the former to the latter, numeral keys for setting up a computation in said computation-accumulating means, a lock for said numeral keys, said general operator having a cam thereon, a bell crank engaging said cam, and means connected to said bell crank for enabling the release of said lock on a movement of said general operator to run up an accumulated computation.
19. The combination with computation-accumulating means, of computation-registering means, a general operator for transferring an accumulated computation from the former to the latter, a series of numeral keys for setting up a computation in said computation-accumulating means, a lock for said numeral keys, said general operator having a cam shoulder thereon, a bell crank engaging said cam shoulder, a link having a pin-and-slot connection with said bell crank, a second bell crank connected to said link to be actuated thereby, and a rod engaging said lock to determine the effectiveness thereof, said rod being moved to release said lock when said general operator moves to run up an accumulated computation in said registering means.
20. In a combined typewriting and computing machine, the combination with temporary registering means, of computation-accumulating means, means for transferring temporarily registered computations from the former to the latter, a series of typewriter keys for actuating said registering means, a traveling typewriter carriage, a jack, a carriage normally controlling said temporary registering means and said jack during a portion of its movement, means for locking said keys against actuation after all the digits of a number have been registered in said temporary registering means and before they have been run up in said accumulating means and means for making said jack ineffective at will even though the temporary registering means is still effective by said carriage during said portion of its movement.
21. The combination with a traveling carriage, of temporary registering means, computation-accumulating means, means for transferring a temporarily registered computation from the registering means to the accumulating means, a series of jacks actuated by said carriage for controlling the action of said temporarily registering means, a series of numeral keys for setting up numbers in said temporary registering means, and a jack alongside said first-mentioned jacks and operated by said carriage to lock said keys against actuation after all the jacks in the series have been actuated to temporarily register a number set by said keys and before said number is accumulated.
22. The combination with a series of computing wheels, of a series of numeral keys, temporary registering means actuated by said numeral keys for registering a computation digit by digit, means for running up all the registered digits of a computation concomitantly in said computing wheels, a lock universal to said keys, a traveling carriage, a denomination selector on said carriage, a series of jacks forming part of the computation devices, and operated by said selector and a jack also operated by said selector as said carriage passes from the column in which the units digit is written, said jack being connected to actuate said lock.
23. In a combined typewriting and computing machine, the combination with temporary registering means, of computation-accumulating means, a general operator for transferring a temporarily registered computation from the latter to the former, numeral keys for setting up a number digit by digit in said temporary registering means, a lock for said numeral keys operable by the typewriting mechanism, means forming part of the computing mechanism and normally tending to actuate said lock, and a latch for holding said last-mentioned means against actuation, during the operation of said temporary registering means.
24. In a combined typewriting and computing machine, the combination with temporary registering means, of computation-accumulating means, typewriter keys, means for transferring a temporarily registered computation from the former to the latter, a lock effective on said keys for notifying the operative that all the digits of a number to be computed have been registered and not run up in said accumulating means, means for automatically releasing said lock as an incident to the running up of a number in said accumulating means, and means for rendering said lock ineffective so as to prevent the same from acting when a registered number has not been run up in said accumulating means.
25. In a combined typewriting and com-

puting machine, the combination with computing wheels, a single set of numeral keys and a traveling carriage, of a denomination selector forming part of said traveling carriage and determining how said keys shall be effective on said wheels, a lock for said keys, a device for automatically making said lock effective controlled from said denominational selector when a key has determined 5 how the units computing wheel shall be operated, and means for silencing said lock-controlling device at will, while leaving said selector free to control said wheels.

26. In a combined typewriting and computing machine, the combination with numeral keys, computing wheels and a traveling carriage, of a denomination selector controlled by said carriage for determining how said keys shall be effective on said wheels, 10 means whereby said denomination selector may be set to ineffective position, an obstructing means for said keys, a device acting through the medium of said selector for automatically making said obstructing device effective when a key has coöperated 15 with said selector to determine how the units wheel shall operate and means for making said obstructing device ineffective at will independently of the selector, whereby 20 in any column on the work-sheet, computation may be rendered effective or ineffective at will and key locking may be also rendered effective and ineffective at will independently of the computing operation.

27. In a combined typewriting and computing machine, the combination with alphabet and numeral keys and computing wheels of a traveling carriage, hooks connected to said keys, a line-locking device 25 coöperating with said hooks to lock all of said keys, means controlled from said carriage for rendering said line-locking means effective when a key has determined how the units wheel shall be operated, and means 30 for rendering said carriage control ineffective on said line-locking device while leaving said device free to operate in the usual manner at the end of a line.

28. In a combined typewriting and computing machine, the combination with a line-locking device for the typewriter, of a denomination selector for the computing device, means whereby said selector controls said line-locking device, and means for making said selector ineffective on said line-locking device without altering its effectiveness as a selector.

29. In a combined typewriting and computing machine, the combination with a

line-locking device for the typewriter, of a 60 denomination selector for the computing mechanism, a latch forming part of the computing mechanism normally holding said line-locking device ineffective, means controlled by said selector for releasing said 65 latch, and means for making said latch-releasing means ineffective at will.

30. In a combined typewriting and computing machine, the combination with a line-locking device for the typewriter, of a 70 denomination selector for the computing mechanism, a latch forming part of the computing mechanism normally holding said line-locking device ineffective, means controlled by said selector for releasing said 75 latch, means for making said latch-releasing means ineffective at will, a general operator for forming part of said computing mechanism, a cam forming part of said general operator, and a bell-crank operated by 80 said cam for putting said line-locking device under the control of said latch.

31. The combination with numeral keys, of a traveling carriage controlled thereby, 85 automatic means controlled by said carriage for locking said keys when a number has been completely registered thereby, means controlling said locking means locatable at a point intermediate the limits of travel of said carriage, and settable means 90 for making said automatic carriage controlled means ineffective.

32. In a combined typewriting and computing machine, the combination with a carriage and numeral keys having means to 95 control said carriage, of computing mechanism, a series of jacks forming denominational devices operable successively by said carriage, a supernumerary jack and means connected thereto and operable by said carriage 100 for obstructing the operation of the keys.

33. In a combined typewriting and computing machine, the combination with numeral keys and computing mechanism controlled thereby, of means for obstructing the operation of said keys brought into action when a number has been completely set up by operation of a sufficient number of keys, 105 operating means for said obstructing means and means settable at will for rendering said operating means effective or ineffective 110 on said obstructing means.
